UNITED STATES PATENT OFFICE.

GEORGE P. FENNER, OF NEW LONDON, CONNECTICUT.

SHEET-DELIVERY DEVICE FOR PRINTING-PRESSES.

1,099,641.

Specification of Letters Patent.

Patented June 9, 1914.

Application filed February 20, 1914. Serial No. 819,872.

To all whom it may concern:

Be it known that I, GEORGE P. FENNER, a citizen of the United States, and a resident of New London, in the county of New London and State of Connecticut, have invented a certain new and useful Sheet-Delivery Device for Printing-Presses, of which the following is a specification.

My invention relates to a mechanism for delivering sheets from the impression cylinder of a printing press upon a delivery board, either printed side up or printed side down. Devices have been in use for delivering the sheets printed side up; and others have been in use for delivering printed side down; but my present invention embodies a device by which either of these operations may be performed on the same press as requirements demand.

The principal object of my invention is to provide a combined delivery in which all of the principal advantages of the most approved printed side up, as well as printed side down devices may be retained and utilized.

Another object of my invention is to provide a combined arrangement in which the change from one kind of delivery to the other may be effected in a simple and efficient manner and with the aid of means which are mechanically efficient.

Another object of my invention is to employ tapes in the printed side down or fly delivery device which may also be utilized to keep the sheets upon the tapes of the printed side up delivery device.

Another object of my invention is to provide an arrangement in which the change from one kind of delivery to the other may be effected without altering the location of the fly fingers, their shaft and the gears which operate them.

Another object of my invention is to make it not only possible to effect the change from one delivery to the other, in a very simple manner, but to provide an arrangement wherein the possibility of interference from improper manipulation is avoided.

Another object of my invention is to provide an arrangement wherein the shifting of some of the parts necessary to the change from one delivery to the other will be effected at the same time and through the same operating parts, as to both the printed side up and printed side down devices.

Another object of my invention is to pro-

vide effective means for stationarily holding the fly fingers out of operative position while the mechanism is being used for delivering sheets printed up.

Another object of my invention is to provide simple and effective means for throwing out of operation those parts of the complete mechanism which do not take part in the operations during the delivery of the sheets printed side up or printed side down.

Another object of my invention is to make the tapes of the fly device reversible in their operation so that they may be utilized when either form of delivery is in operation.

Another object is to make the reversal of these tapes effective automatically as the shift is made in the parts from one form of delivery to the other.

Another object of my invention is to arrange for the shifting of the position of the tapes of the delivery devices, from either side of the machine.

Other advantages derived from my invention will be set forth in the detailed description hereinafter.

In the drawings forming part of this application, Figure 1 is a plan view of the invention as applied to a flat bed printing press, Fig. 2 is a similar view, on an enlarged scale, with parts broken away to show other parts lying below them, Fig. 3 is a side elevation, Fig. 4 is a sectional view, showing the principal parts of the tape devices and the fly fingers in elevation, Fig. 5 is a diagrammatic view, showing the arrangement of the tapes, Fig. 6 is an end view of the sheet delivery devices, looking at the left hand end of Fig. 3, Fig. 7 is an enlarged elevation of that branch of the mechanism which lies near the impression cylinder; and it shows the parts in position to operate for printed side down delivery, Fig. 8 is a view, looking at the left hand end of Fig. 7, Fig.

9 is a detail view of one of the clutches for controlling the tape shafts, Fig. 10 is a view similar to Fig. 7, but on a smaller scale, and showing the parts in position to operate for printed side up delivery, Fig. 11 is a sectional view, of a similar part of the ma-

chine and showing the rollers near the impression cylinder, Fig. 12 is an end view, and Fig. 13 is a plan view, of the adjustable tape tighteners, Fig. 14 is a side elevation of the parts shown in Fig. 13, Fig. 15 is an enlarged elevation of the means for disconnecting the drive from the fly fingers. 16 is a front elevation and Fig. 17 is a plan view, of the device for holding up and out of operation, the carriage operating rod.

I prefer to employ the principal features 5 of the devices shown in my U. S. Patents Nos. 335,066 and 604,974 for delivering the sheets printed side up, although this is not imperative.

I have shown the stationary frame 1 of a 10 flat bed printing press of ordinary construction, having standards 2 for supporting the impression cylinder 3; and the standards 4 for supporting the sheet delivery mechanisms. It is to be understood that the press 15 may be of any ordinary or special construction as my present invention necessitates no changes in the construction of the press proper. The printed sheets are received from the impression cylinder first upon the 20 guide fingers 5 from which they pass between the cutter rollers 6, 7, driven in the usual manner; and from these the sheets pass onto the sheet delivery device to be delivered either printed side up or printed side 25 down, according to the positioning of the parts hereinafter described. There may be cutter rollers 6, 7, arranged upon the shafts 8, 9, for engaging the margins of the sheets and there may be intermediate cutter rollers 30 for engaging the middle of the sheet if desired, according to present practice.

That branch of the mechanism which delivers the sheets printed side up consists of the following: There are supporting tracks 35 or rails 10, 11 arranged at each side of the press, and they extend from a point near the impression cylinder to and over the delivery board 12. The tracks 10 are preferably stationary; while the tracks 11 are stationary 40 during the operation of the machine, but they may be racked backwardly and away from the cylinder to fold in relation to the tracks 10; for the purpose of providing easy access to the impression cylinder and associated parts. There is a shaft 13 journaled 45 in the side frames of the machine, which shaft is provided with an operating crank 14; and gears 15 near each end of the shaft mesh with the rack teeth 16 on the under- 50 sides of the tracks 11. This feature of a folding track is not, *per se*, new in the present case, as it is shown and described in my said Patent No. 604,974. The carriage for delivering the sheets upon the delivery board 55 is reciprocatable along the tracks 10, 11. The carriage consists, primarily, of the rails 17, 18, having flanged wheels 19 secured near one end and traveling on the track rails 10; and having other flanged wheels 20 traveling 60 on the track rails 11. By means of the tracks and the wheels the carriage is supported and guided in its reciprocations from a position near the impression cylinder to a position over the delivery board. There 65 is a shaft 21 near the impression cylinder

which has a tape pulley 22 over which travel the endless tapes 23 of the printed side up device, there being a number of these tapes arranged side by side in the same plane across the machine. The pulley 22 is not 70 movable with the delivery carriage although it is shiftable in position, as will be later pointed out. There is a shaft 24 near the other end of the device that is, over the delivery board, and arranged below the tape 75 carriage; and this shaft carries the pulley 25 over which the tapes 23 also engage. This pulley, 25, is also stationary as to the travel of the carriage. The carriage itself has a shaft 26 near its front end, which carries 80 another tape pulley 27 which travels with the carriage and above the pulley 25. The tapes 23 engage around this pulley 27. There is another shaft 28 and pulley 29 arranged near the rear end of the movable 85 carriage; which travel with the carriage, and in a horizontal plane, between the planes of the pulleys 27 and 25; since they are to pass between the latter. The endless tapes 23 pass from the pulley 22 to the pulley 27, 90 this portion forming the active or sheet holding runs of the tapes; from the pulley 27 they pass to the pulley 29; from the latter to the rear stationary, pulley 25; and from the latter, rear to the pulley 22. Upon 95 the shaft 21 there is arranged a clutch device 30 for permitting the pulley 22 to turn left hand in Fig. 5, and for preventing it from turning right hand. There is a similar clutch device 31 on the shaft 26 of the 100 pulley 27; for preventing this pulley from turning right hand, and for permitting it to turn left hand, in Fig. 5. The pulleys 22, 27, therefore, both turn to the left but cannot turn to the right; but the clutches 105 30 and 31 may be effective at different times, as will be made apparent. When the movable carriage is approaching its rear position near the impression cylinder 3, the sheet from the impression cylinder is fed out between the cutter rollers 6, 7, and over the pulley 22 upon the upper run of the tapes 23; and during the time the carriage is moving forwardly away from the impression cylinder the sheet is deposited full 110 length upon the tapes. When the carriage is moved to the left in Figs. 3 and 4, for the purpose of carrying a previously deposited sheet over the delivery board, the pulley 27 moves away from the pulley 22; and the pulley 29 moves toward the pulley 25. The separation of the pulleys 27 and 22 will cause them to draw in opposite directions upon the upper run of the tapes 23; and the tapes must pay off one or the other pulley. 115 Since the clutch 31 prevents the pulley 27 from turning right hand in Fig. 5, this pulley will draw the tapes (upper run) from the pulley 22; and this is possible because the pulley 22 is permitted, by the clutch 30, 120

125

130

to turn left hand. The result of this arrangement is that, as the carriage moves forwardly the pulley 27 moves away from the stationary pulley 22, drawing upon the 5 upper run of the tapes and causing the latter to pay off the latter pulley. The upper run of the tapes by this operation is extended in length, the sheet traveling forwardly with the tapes. During this forward movement of the carriage the pulley 29 is moving toward the pulley 25; and, consequently, the run 32, of the tapes is shortening to the same extent that the upper run 34 is being extended. The pulleys 15 change their relative positions to lengthen the upper run of the tapes so that these extend, when the carriage has reached its extreme forward position, from the pulley 22 to the front end of the delivery board. 20 During this movement of the carriage, the sheet previously deposited upon the tapes is carried forwardly, therewith, and with the carriage, to a position over the delivery board. When the carriage is reversed in direction and moves backwardly toward the impression cylinder again a different action 25 takes place. In this movement the rearwardly moving pulley 29 must extend the run 32, of the tapes and to do so it must take the tapes from another run. Since the 30 clutch 30 only permits the pulley 22 to turn left hand, the extension of the run 32 must be made by leaving the upper run stationary relative to the carriage and by taking up part of it for the extension of the run 32. In this operation the tapes peel off under the sheet which has been positioned over the delivery board; and, as the carriage 35 simultaneously moves rearwardly, the sheet 40 is deposited upon the delivery board, printed side up. During the forward movement of the carriage a sheet feeds through the cutter rollers and upon the tapes and behind a previously deposited sheet, ready 45 to be carried forward to the delivery board. These operations are periodically repeated so long as the printed side up device is in operation.

The clutches for controlling the shafts 50 21, 26 are shown in Fig. 9. Each consists of a disk 35 keyed to the respective shaft; and of a ring or cage 36 partially inclosing it. The disk 35 has the ball races 37, in which lie the balls 38. Springs 39 acting 55 on these balls tend to move them into a position which will cause them to impinge between the disk 35 and the cage 36. A pin 40 on an extension of the cage, engages parts relatively to which the respective 60 shafts revolve. In the case of the clutch 30 the pin engages a handle 42; whereas the pin of the clutch device 31 engages the rail 17 (Figs. 1 and 2). Viewing the parts as shown in Fig. 9, if the shaft and the disk 65 35, tend to turn right hand the balls are

moved along the races 37 which causes them to impinge between the disk and the cage and prevent the disk and shaft from revolving. The disk and shaft are free to turn to the left, however, because this movement advances the balls into the wider portions of their races and permits the disk and shaft to turn freely. 70

The carriage is reciprocated by the following arrangement: Upon a shaft 43 mounted in the standards 4 there are carried similar gears 44, arranged near opposite sides of the machine; and upon the same shaft there is a gear 45. A casting 46 is held upon this shaft; and it forms a housing for the gear 45 and a bearing for the sliding rod 47. The upper end of this rod 47, has rack teeth 48 which mesh with the teeth of gear 45; so that when the rod is reciprocated the gear and its shaft are oscillated. The 80 gears 44 mesh, respectively, with similar gears 49 mounted upon the studs 50. These latter gears, in turn, mesh with the rack teeth 51 on the under sides of the rails 17, 18, of the reciprocating carriage. From the 85 above it will be apparent that the reciprocations of the rod 47 cause the oscillation of the gears 45 and 49 and through these, the reciprocation of the carriage. 90

In Figs. 3, 16 and 17 I have shown the device for disconnecting the carriage and for holding it out of operation. The rod 47 has an open hook 109 which engages a pin 110 on the crank arm 111, which is secured upon the shaft 91. When the carriage 95 is to be thrown out of operation the hook 109 is disengaged from the pin 110 and the rod is raised into position to be held by a supporting device. The latter comprises a pin 112 fixed in the side frame of the press 100 and provided with a rocking portion 113 hinged at 114 in such a manner as to be movable upwardly but not below the horizontal. The member 113 is swung upwardly 105 into the dotted line position of Fig. 16 to 110 allow the rod 47 to pass it; and when this has been done the pin 113 is lowered to the horizontal position to support the rod. The carriage may be moved by hand, up 115 close to the impression cylinder, with the rod 47 sliding on the pin 113, until the hook 109 engages the pin. The carriage will then be firmly held in position while the fly delivery is in use. This forms a very convenient arrangement for positioning and locking the carriage. There is a washer 115 arranged upon the pin 113. When it is desired to rack back the tracks 11 by operating the crank 14, the rod 47 is first raised 120 above the pin 113 in the manner just described and the rod is allowed to rest upon the washer. As the tracks and carriage are racked backwardly the rod 47 rests upon the freely revolving washer. This arrangement 125 makes it unnecessary for an attendant 130

to hold up the rod 47 during the racking back of the track and carriage.

The cam 90 is secured to a portion of the crank arm 111 by means of a bolt 116, which is adjustable along the slot 117. To adjust the fly delivery for different size sheets it is simply necessary to loosen the bolt 116, adjust the position of the cam on the shaft and tighten the bolt again. If small sheets 10 are being printed the cam will be adjusted to make the fly fingers advance sooner in relation to the printing operation so that the sheet will be carried over as soon as it is entirely over the fly fingers; whereas when 15 larger sheets are being printed the reverse adjustment of the cam is made to delay the throw of the fly fingers sufficiently to allow them to receive the larger sheets.

The shaft 21 which carries the forward 20 and non-traveling tape pulley 22 is journaled in the similar lever arms 52 which fulcrum upon studs 53 secured in the tracks 11. There is a handle 42 on each of the arms 52 for rocking the levers to place the 25 shaft 21 and its pulley, in either an upper or lower position. The parts are secured in either of these positions by means of a bolt 54 passing through apertures in the rails and through either of the apertures 55 30 in levers 52 which support the shaft 21. When the pulley 22 is placed in its higher position the bolts 54 are engaged in the higher apertures 55 to firmly hold it in position; and when the pulley is to be placed 35 in its lower position the bolt is removed, the pulley lowered, and the bolts are entered in the lower apertures 55 to firmly hold the pulley in position. When the pulley is placed in the upper position, as shown in 40 Fig. 11, the tapes 23 are in position to receive on their upper runs 34 the sheets fed through the cutter rollers. This is the case when the printed side up delivery is in operation. When the pulley 22 is placed in its 45 lower position the tapes 23 will be below the receiving position and will perform no function in the delivery of the sheets.

The fly device for delivering printed side down is arranged as follows:—The fly fingers and operating parts are preferably 50 mounted on the stationary parts of the machine so that they need not partake of the reciprocations of the carriage. In the upper arms of the adjustable levers 56 there is 55 journaled a shaft 57 which carries any desired number of tape pulleys 58. There is a shaft 59 movable up and down in a slotted journal 60 near the rear end of the device, preferably over the shaft 21. This shaft 59, 60 carries tape pulleys 61, corresponding in numbers and positions with the pulleys on the shaft 57. There are endless tapes 62 engaging over the pulleys 58 and 61. These tapes lie above the tapes 23. They serve to 65 receive the printed sheets from the cutter

rollers when the device is operated to deliver printed side down; and they coöperate in this respect with the fly fingers, the latter being adapted to take the sheets from the tapes, as will appear. The tapes 62, in addition to serving as part of the fly, coöperate with the tapes 23 of the printed side down delivery to prevent the sheets from blowing up from the latter tapes.

There is a large gear 63 on the impression cylinder, which drives an intermediate gear 64; and the latter, in turn, drives the gear 65 arranged upon the shaft of the lower cutter rollers. In this manner the operating power is applied to the lower cutter rollers. 70 The upper cutter rollers have their shaft 8 arranged in a slotted bearing 66 so that these rollers 6, rest upon and are driven, frictionally by the lower rollers 7. The gear 65 also drives a gear 67 mounted upon a 80 shaft 68 in the bracket 69. This latter gear is adapted to drive the tapes 62 when the printed side down delivery is in operation; but when the printed side up delivery is in operation these tapes are driven in a 90 reverse direction. When the shaft 59 is in its lower position the gears 70 carried thereon are in mesh with the gears 67 and are driven by them. At such times the tapes 62 are operated so that their upper runs 95 travel away from the impression cylinder in the direction necessary to carry away the sheets. At such times, the shaft 21 is idle because the carriage is not then driven. When the shaft 21 is in its higher position, 100 as when the printed side up delivery is in operation, the gears 70 of the shaft 59 and the gears 71 of the shaft 21 are in mesh; and the gears 70 and 67 are out of mesh. At such times, therefore, the shaft 59 is no 105 longer driven from the impression cylinder, but is driven from the shaft 21. At such times the shaft 21 is intermittently driven through the action of the reciprocating carriage and the advancing of the tapes 23, 110 previously described.

From the above it is apparent that when the printed side down fly delivery is in operation the shaft 21 and the tapes 23 remain idle; and the shaft 59, driven from the impression cylinder, causes the tapes 62 to travel in the direction indicated by the arrows in Fig. 7. When the printed side up delivery is in operation the lower runs of the tapes 62 travel to the left in the drawings 115 whereas, when the shaft 59 is operated from the impression cylinder, as in delivering printed side down, the upper runs of these tapes travel to the left. The shifting of the shaft 21 to alter the position of the tape 120 pulley 22 simultaneously shifts the shaft 59 and changes its drive. On the shaft 21 there are rollers 72, in line with rollers 73 on the shaft 59. When either of the handles 42 125 is operated to raise the pulley 22 from the 130

lower to the upper position, the rollers 72, come into contact with the rollers 73 and then the shaft 59 and its pulleys and tapes are raised to the position shown in Fig. 10. 5 This brings the tapes 62 above the path of the sheets and brings the upper runs of tapes 23 into position to receive and transfer the sheets. This also disengages the gears 70 from the gears 67 and engages them with the 10 gears 71; so that the shaft 59 is then operated from the shaft 21 instead of from the impression cylinder. To change from one drive to the other it is only necessary in this branch of the mechanism, to operate either of the handles 42 from either side of the machine, to either raise or lower both sets of tapes and their rollers and to reverse the operation of the upper tapes.

The lever 56 which carries the shaft 57, 20 is adjustable by means of the screw 74 engaging in the slot 75, for the purpose of taking up slack in the tapes 62.

Over the carriage and in the stationary side frames 4 there is journaled the fly shaft 25 76, which preferably has a fixed position. There are secured to this shaft a number of fly fingers 77 of novel arrangement. These fingers are secured to the shaft, preferably by means of curved castings 78 and 30 bolts 79, in such a manner that the fly fingers will lie in an offset position in relation to their shaft; that is, the top surfaces 77 of the fingers do not lie tangent to the shaft, but tangent to a circle larger than the shaft. 35 These fly fingers are so positioned on their shaft that they may rock down to a position below the upper runs of the tapes 62 in order to receive the printed sheets. When the printed side up delivery is in operation 40 the fly fingers are held in the position shown in Figs. 3 and 4 so as to be out of the way of the sheets and tapes. There is a bolt 80 which is entered in a socket 81 of the frame; and it extends into an aperture in 45 the shaft which is so positioned that the shaft and fly fingers will be held by the bolt in the inoperative position shown in Figs. 3 and 4. There is a handle 82 on the end of the shaft for turning the latter to find 50 the right position for the entry of the bolt 80 into the shaft aperture.

There is a casting 83 mounted on the shaft 76; and it comprises a housing 84 for the gear 85 arranged on the shaft; and it 55 also comprises a journal or socket for a reciprocating rod 86. The latter has rack teeth 87 which mesh with and operate the gear 85, and, therefore, the fly shaft and fly fingers. When the fly delivery is to 60 be used, the bolt 80 is removed from the socket 81 and is inserted into an aperture in a disk 88 which is fast on the fly shaft, and in a corresponding aperture in the gear 85. This locks the disk and gear together 65 so that the fly shaft will be oscillated as the

rod 86 reciprocates. But when the bolt is removed from the latter position and placed in the socket 81, the gear 85 simply turns idly on the shaft and the fly fingers remain idle. This forms a simple and effective arrangement for connecting the fly for operation or for disconnecting it and holding it out of the way. 70

The lower end of the rod 86 is fulcrumed to one arm of a lever 87 which rocks from the fulcrum 88. The other arm of this lever carries a roller 89 which travels in contact with the cam 90 on the main shaft 91. There is a spring 92 surrounding the rod 86 which always tends to force the latter upwardly; and this spring causes the roller 89 to follow the cam 90. 80

To throw the fly device out of operation there is an eccentric 92 arranged on a stud 85 and operated by a handle 93. The stud is inserted in an aperture in the side frame and the handle is turned down so that the eccentric forces down the lever 87 to a position which will keep the roller 89 off its cam. When the eccentric is removed the lever is allowed to follow the cam under the action of its operating spring 92. Through this arrangement all parts of the fly delivery may be thrown out of operation while the printed side up delivery is in use. 90

The arms 93 carry a bar 94 on which the fly fingers may rest at their extreme lower position. Between the same arms 93, there is arranged a bar 95, which supports a number of fingers 96 which may be adjusted around the bar to make their forward ends lie close to or separated from the plane of the upper runs of tapes 23. If there is a tendency of the sheets to slide forwardly over the tapes 23 when coming from the cutter rollers, these fingers 96, are set near the margins of the sheets and with their forward ends near the tapes, so that the sheets will be held in contact with the tapes and so that they will stop when the tapes stop. 100

I prefer to employ an additional arrangement for holding the sheets at the delivery end of the carriage. For this purpose I have shown shafts 97 and 98 carried by the carriage, the latter shaft being slightly lower than the former. There are pulleys 99, 100 on these shafts, respectively, over which travel the tapes 101. There are gears 102 on the shaft 26 of the tape pulley 27; and, these gears mesh with the gears 103 on the shaft 98. Through these members the tapes 101 are driven from the shaft 26 so that they travel at the same speed as the tapes 23. The tapes 101, as will be seen in Fig. 5, engage around a portion of the pulleys 27 to hold the leading edge of the sheet from rising and to cause the sheet to turn downwardly toward the delivery board. 115

In Figs. 12, 13 and 14 I have shown a novel arrangement for keeping the tapes 23 120 130

individually taut under all conditions. There is a bar 104 arranged between the carriage rails 17, 18, for supporting the tighteners. Each tightener consists of a yoke 105 partially surrounding the bar; of a square rod 106 sliding in apertures in the depending arms 107 of the yoke; and of a spring 108 for forcing the rod forwardly. The tape pulleys 29 are carried on these rods 106, so that the springs 108 keep the tapes 23 under proper tension at all times. The adjustment of the tapes 23 laterally of the machine to adapt them to the different sheets is facilitated by the above arrangement. When the tapes are shifted, the yokes 105 and connected parts are simply slid along their bar 104 to any desired position.

Operation: To operate the device for delivering printed side up the parts should be arranged as follows: The fly fingers 77 are held in the position shown in Figs. 3 and 4 by the bolts 80 engaging in the apertures in the fly shaft; the shaft 76 is disconnected from the gear 85; and the roller 89 is held off the cam 90 by the action of the eccentric on the lever 87. In this condition the fly fingers can not operate. The tapes and their various pulleys will be positioned as shown in Figs. 3, 4, 10 and 11. The pulley 22 will be in its upper position, so that the upper runs of the tapes 23 will be in position to receive thereon the printed sheets as they come from the cutter rollers. The shaft 59 and its pulley 61 will be in their higher position, being held up by the rollers 72, 73, which also hold the shafts 21 and 59 separated sufficiently to space the tapes 23, 62 to allow the sheets to pass freely between them. In this position of the shaft 59 and its pulley, the lower runs of the tapes 62 will lie just above the upper runs of the tapes 23. In this position of the parts the gear 71 will operate upon the gear 70 to drive the pulley 61 and its tapes. The latter will be so operated that their lower runs will travel in the same direction as the upper runs of the tapes 23, *i. e.* in the direction of travel of the sheets. The tapes 62 therefore, will coöperate to keep the sheets from blowing or rising up from the tapes 23. In this respect I am able to utilize part of the printed side down device in coöperation with the printed side up device. The sheets will now be delivered by the tapes 23 upon the delivery board, printed side up, as the carriage reciprocates back and forth; in the manner previously set forth. If it is desired to change to the fly delivery the following changes will be made: The rod 47 will be disconnected from the arm on the main shaft and it will be connected with the pin so that the carriage will no longer reciprocate but will be held up close toward the impression cylinder. The bolt 80 will be taken out of the socket 81 and will be placed into the

apertures in the disk 88 and gear 85 to couple these members together. The eccentric 92 will be thrown over, and removed to allow the lever 87 to be rocked by the cam 90. The bolt 54 will be removed, and either of the handles 42 will be operated to rock the levers 52; after which the bolt will be re-entered in the lower aperture 55. This operation of the levers 52 is to move the shaft 21 and its associated parts downwardly. The result of this is to move the tapes 23 out of the sheet receiving position. As the shaft 59 follows down part way with the shaft 21 it comes to rest on its bearing 60, in such a position as to leave the gears 70, 71 disengaged and to place the upper runs of the tapes 62 into position to receive the sheets from the cutter rollers. The lowering of the shaft 59 also throws the gear 70 into mesh with the gear 67; so that the pulley 61 will be operated from the impression cylinder and in a direction reverse to its previous operation. These various alterations need not be made in the exact order here mentioned. The sheets will now be received from the cutter rollers upon the upper runs of the tapes 62. Just previous to the reception of the sheet upon the tapes the fly fingers are lowered by the rocking of the shaft 76; so that the fingers lie between and slightly below the upper runs of tapes 62 as shown in dotted lines in Fig. 4. As the sheet comes upon and is carried along by the tapes 62 it advances over the fly fingers, traveling toward a point above the shaft 76. When the sheet is entirely over the fly fingers the latter rock to the left, carrying the sheet therewith; and they deposit it printed side down upon the delivery board. During this operation only the fly device is active, as the printed side up devices, including the carriage, remain idle. In this respect the operation of the mechanism for either kind of delivery is just as simple as if the devices were separately employed.

Owing to the offset position of the fly fingers relative to their shaft it is possible to mount the latter in a fixed position above the carriage and to carry over and deliver the sheets with the fly without interfering with other parts of the mechanism. Furthermore, the offset arrangement makes it possible not only to receive the sheets on the fly fingers in a simple manner, but the fingers lie parallel with the delivery board as they deliver the sheets, as is shown in dotted lines in Fig. 3.

The change from one delivery to the other is very easily made and the devices for the different deliveries are not unnecessarily complicated by their combination in a single machine.

Having described my invention, what I claim is—

1. In a printing press, the combination

- with the cylinder, of a printed side up sheet delivery device including tapes for receiving the sheets from the cylinder, a printed side down delivery device, including tapes for receiving the sheets from the cylinder, and means whereby said tapes may be shifted to bring the tapes of either of said delivery devices into sheet receiving position. 5
10. In a printing press, the combination with the cylinder, of a printed side up sheet delivery device including tapes for receiving the sheets from the cylinder, a printed side down delivery device, including tapes for receiving the sheets from the cylinder, and means for simultaneously shifting the tapes of both delivery devices to bring the tapes of one delivery device into sheet receiving position and to place the other out 15 of sheet receiving position. 20
15. In a printing press, the combination with the cylinder, of a printed side up sheet delivery device, including tapes for receiving the sheets, a pulley for said tapes arranged near the cylinder, a printed side down delivery device, including tapes for receiving the sheets, a pulley for said latter tapes arranged near the cylinder, and means for shifting said pulleys to bring the tapes 25 of either of said sheet delivery devices into sheet receiving position. 30
20. In a printing press, the combination with the cylinder, of a printed side up sheet delivery device including tapes for receiving the sheets, a printed side down sheet delivery device including tapes for receiving the sheets, said latter tapes being arranged to coöperate with said first mentioned tapes during the operation of the printed side up 35 device, means for shifting the tapes to bring the tapes of either delivery device into position to receive the sheets, and means for reversing the direction of operation of the 40 tapes of the printed side down delivery device. 45
25. In a printing press, the combination with the cylinder, of a printed side down sheet delivery device including tapes having upper and lower runs, and adapted to receive the sheets upon said upper runs, a printed side up sheet delivery device including tapes for receiving the sheets, the lower runs of said first tapes coöoperating with said latter tapes during the operation 50 of the printed side up device, means for shifting the tapes to bring the tapes of either delivery device into position to receive the sheets and means for reversing the direction 55 of operation of the tapes of the printed side down device. 60
30. In a printing press the combination with the cylinder, of a printed side down sheet delivery device including tapes for receiving the sheets, a printed side up sheet delivery device including tapes for receiv- 65
- ing the sheets, said first mentioned tapes being arranged to coöperate with said second mentioned tapes during the operation of the printed side up device, means for shifting the tapes to bring the tapes of either delivery 70 device into sheet receiving position, means for operating said first mentioned tapes from said cylinder when they are in the sheet receiving position and means for operating said first tapes from said second mentioned tapes 75 when the latter are in sheet receiving position. 80
35. In a printing press the combination with the cylinder, of a printed side down sheet delivery device including tapes for receiving the sheets, a pulley therefor arranged near the cylinder, a printed side up sheet delivery device including tapes for receiving the sheets, a pulley therefor, said first tapes coöperating with said second tapes during the operation of the printed side up delivery device, means for raising and lowering said pulleys to bring either set of tapes 85 into sheet receiving position, and means for separating said pulleys as they are lowered. 90
40. In a printing press the combination with the cylinder, of sheet delivery devices, including upper and lower tapes for receiving the sheets, a pulley for said lower tapes, arranged near the cylinder, having a shaft, rocking arms carrying said shaft and means accessible at either side of the press for rocking said arms to raise and lower said pulley. 95
45. In a printing press the combination with the cylinder, of printed side up and printed side down sheet delivery devices, both of which are arranged to deliver the sheets upon the same delivery board, each delivery device having tapes for receiving the sheets, and means for shifting the tapes to bring the tapes of either delivery device into sheet receiving position. 100
50. In a printing press the combination with the cylinder, of a printed side up sheet delivery device including tapes, a printed side down delivery device including tapes and fly fingers for taking sheets from said latter tapes, and shifting means whereby the tapes of either delivery device may be 105 arranged to receive the sheets. 110
55. In a printing press the combination with the cylinder, of a printed side up sheet delivery device including tapes and a pulley therefor arranged near the cylinder, a printed side down delivery device including tapes, a pulley therefor near the cylinder, fly fingers mounted on a stationary shaft and adapted to take the sheets from said latter tapes, and means for shifting 115 said pulleys to bring the tapes of either delivery device into sheet receiving position. 120
60. In a printing press the combination with the cylinder, of a printed side up sheet delivery device including tapes and a re- 125

ciprocating carriage, a printed side down delivery device including tapes, fly fingers mounted on a stationary shaft above said carriage and adapted to take the sheets from said latter tapes, and means whereby said tapes may be shifted so that the sheets may be received by the tapes of either delivery device.

13. In a printing press the combination 10 with the cylinder, of a printed side up sheet delivery device including tapes, a tape pulley near the cylinder, and a carriage, a printed side down delivery device including tapes, a tape pulley near the cylinder, and 15 fly fingers for taking the sheets from said latter tapes, mounted upon a stationary shaft above said carriage, and means whereby said pulleys may be shifted so that the sheets may be received by the tapes of either 20 delivery device.

14. In a printing press the combination with the cylinder, of a printed side up sheet delivery device including tapes and a reciprocating carriage, a printed side down sheet 25 delivery device including tapes adapted to coöperate with the said first tapes during the operation of the printed side up delivery, fly fingers for taking the sheets from the second-mentioned tapes, a stationary 30 shaft arranged above said carriage and carrying said fly fingers and means whereby said tapes may be shifted to bring the tapes of either delivery into sheet receiving position.

15. In a printing press the combination 35 with the cylinder, of a printed side up sheet delivery device including tapes and a reciprocating carriage, a printed side down sheet delivery device including tapes adapted to coöperate with said first tapes during the operation of the printed side up delivery, fly fingers for taking the sheets from the second mentioned tapes, mounted above said carriage, means for shifting the tapes to bring the tapes of either delivery device into sheet receiving position, and means for reversing the direction of operation of said second mentioned tapes.

16. In a printing press the combination 50 with the cylinder, of a printed side up sheet delivery device including tapes and a reciprocating carriage, a printed side down sheet delivery device including a shaft mounted above said carriage, fly fingers carried upon said shaft and arranged in an offset position in relation thereto, said fly fingers and said carriage delivering to the same delivery board, and means for placing either delivery into operative relation with the cylinder.

17. In a printing press the combination 60 with the cylinder, of a printed side up sheet delivery device, including tapes and a reciprocating carriage, a printed side down

sheet delivery device including tapes, a shaft 65 mounted above said carriage, fly fingers carried upon said shaft, arranged in an offset position in relation thereto, said fingers being adapted to take the sheets from said second mentioned tapes, and means for 70 shifting the tapes to place the tapes of either delivery into sheet receiving position.

18. In a printing press the combination 75 with the cylinder, of a printed side up sheet delivery device including tapes and a reciprocating carriage, a printed side down sheet delivery device including tapes arranged above said first tapes, fly fingers arranged above said carriage for taking the sheets from said second mentioned tapes, means for oscillating said fly fingers to deliver the sheets, means for stationarily holding the fly fingers above the tapes, and means for placing the tapes of either delivery device into sheet 80 receiving position.

19. In a printing press the combination 85 with the cylinder, of a printed side up sheet delivery device comprising forward track rails, rear track rails near the cylinder adapted to be moved forwardly away from 90 the cylinder, a delivery carriage traveling on said rails, tapes, and a pulley therefor near the cylinder, said pulley being movable with said rear track rails, a printed side up sheet delivery device including tapes, a pulley therefor arranged near the cylinder and movable with said rear track rails, and means for placing the tapes of either delivery device in sheet receiving position.

20. In a printing press the combination 100 with the cylinder, of a printed side up sheet delivery device including tapes and a reciprocating carriage, a printed side down sheet delivery device comprising tapes, and fly fingers for taking the sheets from said latter tapes, means for placing the tapes of either delivery into sheet receiving position, means for oscillating said fly fingers, and means for adjusting the operation of the fly fingers to change the moment of their delivery throw.

21. In a printing press the combination 115 with the cylinder, of a printed side down sheet delivery device, a printed side up sheet delivery device, including tapes and a reciprocating carriage, and means for operating the carriage, including a rack bar operated by a crank, operating upon a gear and adapted to be rocked, and means for supporting the bar when disconnected from 120 its crank, including a movable member adapted to be raised to permit said bar to pass and adapted to support said bar when lowered.

22. In a printing press the combination 125 with the cylinder, of a printed side down sheet delivery device, a printed side up sheet delivery device, including tapes and a re-

5 reciprocating carriage, and means for operating the carriage, including a rack bar operated by a crank, and operating a gear, and adapted to be rocked, and means for supporting the bar when disconnected from its crank, including a movable member adapted to be raised to permit said bar to pass and adapted to support said bar when lowered, and a revolute collar on which said bar is

adapted to rest so that the bar may slide 10 upon its support.

Signed at New London, in the county of New London and State of Connecticut, this 18th day of February, 1914.

GEORGE P. FENNER.
